DISPLAY STAND

John Richard Atkinson, Wigginton, York, England, assignor to Rowntree Mackintosh Limited, York, England

Filed Aug. 11, 1969, Ser. No. 18,610

Term of patent 14 years

Int. Cl. D6—01

U.S. Cl. D80—9

Fig. 5.

FIG. 1 is a perspective view, taken from the top, front and one side of a display stand showing my new design;

FIG. 2 is an elevational view of the side opposite that shown in FIG. 1;

FIG. 3 is a bottom plan thereof;

FIG. 4 is a rear elevational view thereof; and

FIG. 5 is a cross sectional view, taken on the line V—V in FIG. 4.

I claim:

The ornamental design of a display stand, substantially as shown.
